Primary Examiner — Elizabeth A. Albert*(74) Attorney, Agent, or Firm* — Michael Best & Friedrich LLP**(57) CLAIM**

We claim the ornamental design for a blade for a reciprocating saw, as shown and described.

DESCRIPTION

FIG. 1 is a front view of a blade for a reciprocating saw; and, FIG. 2 is a front view of another embodiment of a blade for a reciprocating saw.

The long and short broken lines in the drawings define the bounds of the claimed design and form no part thereof. Portions of the blade for a reciprocating saw shown in evenly spaced broken lines are included for the purpose of illustrating environment and form no part of the claimed design.
